UNITED STATES PATENT OFFICE.

HERMANN FISCHER, OF NEW YORK, N. Y., ASSIGNOR TO C. BRANDES, INC., A CORPORATION OF NEW YORK.

TELEPHONE DIAPHRAGM.

Application filed October 24, 1922. Serial No. 596,629.

To all whom it may concern:

Be it known that I, HERMANN FISCHER, a citizen of Russia, residing at New York, in the county of New York, State of New York, have invented certain new and useful Improvements in Telephone Diaphragms; and I do hereby declare the following to be a full, clear, and exact description of the invention, such as will enable others skilled in the art to which it appertains to make and use the same.

This invention relates to telephone receiver diaphragms for use in double pole telephone receivers.

15 In telephone receivers of the type referred to wherein two poles of an electromagnet are disposed in close relation to a sound producing magnetic diaphragm, it has been found that a certain amount of tone distortion occurs, the extent of which is largely dependent upon the accuracy with which the instrument is constructed.

It has been found that the distortion referred to is due, in part at least, to unbalanced synchronous action or unequal electromagnetic flux fields of the two electromagnet poles. In a double pole telephone receiver diaphragm two quite distinct vibratory areas are created, each resulting from the electromagnetic action of one of the poles. These two vibratory areas, in so far as it has been possible to ascertain, interfere at some point on the diaphragm, usually at the center portion, with the result that 35 distortionary vibrations are set up. These distortionary vibrations, it will be understood, are due to the conjoint non-synchronous or unbalanced action of the two major vibratory areas.

40 One of the objects of this invention is to eliminate these distortionary vibrations and thereby provide a telephone receiver having improved tonal qualities.

Experiments have shown that a narrow 45 aperture of suitable length in the center portion of a diaphragm, so disposed as to effect substantially a physical separation of the two vibratory areas, results in a material reduction of distortion. The aperture in 60 the diaphragm may be straight or curvilinear, or it may have any one of several suitable forms. It is, however, preferable that the aperture be as narrow as practical considerations will permit, first because of

the fact that it forms a break in the magnetic path of the receiver, and second because of the possibility of an excessive amount of foreign matter entering the receiver through the aperture if it be of substantial width. Diaphragms in accordance with this invention have been made with apertures of the order of $10/1000''$, and in all probability they can be produced on a commercial basis with apertures of considerably less width. With such narrow apertures as it is commercially practicable to provide there is no appreciable increase in the reluctance of the magnetic circuit.

55 Apertures approximately corresponding in form to the so-called *f*-holes which are provided in violins and some other musical instruments have been found particularly advantageous in connection with the present invention. A diaphragm having two such *f*-holes and intended for use more particularly in a single pole telephone receiver is disclosed in my Patent 1,486,081, dated March 4, 1924. As explained in the aforementioned patent, a diaphragm provided with one or more of the so-called *f*-holes is 60 rendered capable of more accurately reproducing both the upper and lower notes of the musical scale.

65 The ordinary telephone diaphragm as usually designed is more capable of accurately reproducing the higher notes of the scale by reason of the fact that the higher notes more clearly approach the natural period of the diaphragm, which is usually of the order of 800 or 900 cycles per second. 70 As a result of the relatively high natural period of such diaphragms, the lower notes are substantially attenuated, and accordingly the proportionate volume of all the 75 original tones is not accurately maintained in reproduction.

80 A plain telephone diaphragm of the ordinary type when modified in accordance with the invention of my aforementioned copending application is capable of reproducing the lower notes of the musical scale in materially greater proportionate volume without the reproduction of the higher notes being in any way affected.

85 It has likewise been found that the best 100 results are obtained with the present invention, as in that of my aforementioned copending application, when the aperture is

in the form of an *f*-hole similar to that of a violin, but preferably modified so that its width is as small as practical considerations will permit.

5 Other forms of aperture, some of which are illustrated in the accompanying drawing, give very satisfactory results with a double pole receiver, but it has been quite convincingly determined that the *f*-hole 10 form is superior to any other.

Not all telephone distortion is due to inherent defects in receiver diaphragms; it may arise from any one or more of several causes either in the transmitting or receiving 15 station, and in the case of wire telephony it may be caused by the transmission line. It should not be presumed that a diaphragm, in accordance with the present invention will correct distortion arising from such extraneous sources. Furthermore in the design of the receiving instrument itself there are several important factors contributing to proper reproduction, which are quite distinct from what has already been pointed 20 out. If the receiver is poorly designed, it cannot be expected that its defects will be cured by the use of a diaphragm in accordance with the present invention, although a material improvement may be realized in 25 many instances in spite of weak design.

In the accompanying drawings, Fig. 1 illustrates a telephone diaphragm in accordance with the preferred form of the invention;

35 Fig. 2 is a cross-sectional view of a double pole telephone receiver in which is incorporated a diaphragm of the type shown in Fig. 1;

40 Fig. 3 illustrates a diaphragm constituting a modified form of the invention;

Fig. 4 illustrates another diaphragm constituting a modified form of the invention; and

45 Fig. 5 illustrates still another modified form.

The telephone receiver shown in cross section in Fig. 2 comprises a casing 1 in which is mounted a permanent magnet 2, having two polepieces 3 and 4, respectively, 50 forming cores for the electromagnet windings 5 and 6. The diaphragm 7, which is preferably like that shown in Fig. 1, is mounted in close juxtaposition to the ends of polepieces 3 and 4, and cap 8 is provided 55 for securing diaphragm 7 in place. The diaphragm as shown in Fig. 1 is provided at its center with a narrow curvilinear aperture 7^a, somewhat similar in form to the so-called *f*-holes, which are ordinarily provided in violins, and by reason of this similarity this aperture will be hereinafter referred to as an *f*-hole. In Fig. 3 diaphragm 8 is provided with an aperture 8^a, of a form similar to the letter Z. In Fig. 60 4, the diaphragm 9 is provided with an aper-

ture 0^a of wave form, and in Fig. 5 the diaphragm 10 is provided with a straight aperture 10^a.

On account of the fact that the apertures 7^a, 8^a, 9^a and 10^a are interposed in the magnetic path of the receiver, as will be readily recognized, each of these apertures is preferably made as narrow as practical considerations will permit. By practical considerations is meant the physical limitations 75 imposed by reason of the difficulty of producing extremely narrow apertures commercially.

In Fig. 5 the dotted lines represent approximately the two vibratory areas of the 80 diaphragm which are individual to the pole-pieces 3 and 4. Since one of the objects of this invention is to substantially prevent interference between the two vibratory areas, it will be evident that the lengthwise dimension of the aperture should be sufficient to 85 so function. It is, however, preferable that this dimension should not be greatly in excess of this requirement, because the reluctance of the magnetic path of the receiver increases with any increase in the length of the aperture, due to the fact that part of the flux finds a path through the diaphragm beyond the extremities of the aperture, and any increase in the length of the aperture 90 decreases this path.

Of the four forms of apertures shown, Figs. 1, 3, 4 and 5, that of Fig. 5 is the least satisfactory. The apertures of Figs. 3 and 4 are about equal in effectiveness and are 100 considerably better than that of Fig. 5, while the *f*-hole of Fig. 1 is substantially better than any of the other apertures. No exact dimensions of apertures appear to be essential to the successful operation of 105 the invention, but it may be stated that in experiments which have been conducted good results have been obtained with a diaphragm 2 1/8" in diameter and .006" thick 110 in which the overall lengthwise dimension A of the *f*-hole (see Fig. 1) was approximately 11/32"; the overall width B was approximately 3/32"; the width of the aperture was approximately 10/1000"; and the diameter of the end openings approximately 3/64". The overall lengths of the apertures of Figs. 3, 4 and 5 may be approximately the same as that given for the overall length of the *f*-hole of Fig. 1. The overall widthwise dimensions may be proportionately as shown. It will be understood that the dimensions suitable in any particular case are dependent largely upon the size of the magnet cores 3 and 4 and the separation therebetween. In the experiments referred to the lengthwise dimension C of each of the magnet cores was 115 .565", the width D was .050", and the center-to-center dimension E was .375". At 120 the present time the dimensions for each 125 130

particular case can be best established by experiment, no empirical rule having as yet been formulated.

According to the theory of the action of the diaphragms 7, 8 and 9 of Figs. 1, 3 and 4 respectively, the reason for the lower notes of the musical scale being accentuated is that the integral projecting portions 7^a, 7^c, 8^b, 8^c and 9^b have lower natural periods than the remaining portions of the respective diaphragms. This theory seems to have been well established by the experiments which have been conducted, but its accuracy is not at all essential to the complete disclosure of the invention, and it is not desired that this theory be construed as imposing any limitation upon the scope of the invention.

The reason for the better results obtained with the *f*-hole of Fig. 1 than with the apertures of Figs. 3 and 4 is not well established, but it is conjectured that further experiments will show that a diaphragm in accordance with Fig. 4 can be made which will give equally as good results as that of Fig. 1.

I claim:

1. In a telephone receiver, a diaphragm, a pair of electromagnet poles disposed in operative relation to said diaphragm, said diaphragm being provided with an elongated *f*-shaped aperture at its center portion dividing said diaphragm into two portions joined on opposite ends of said elongated *F* shaped aperture forming two adjacent areas arranged to be set into vibration by the actuation of said poles, said elongated *F* shaped aperture operating to substantially prevent interference between the

vibrations set up in said areas when said areas vibrate non-synchronously.

2. In a telephone receiver, a diaphragm, a pair of electromagnet poles disposed in operative relation to said diaphragm, said diaphragm being provided with an elongated aperture at its center portion consisting of a narrow slot integral with said diaphragm and constantly varying in direction, said slot dividing said diaphragm into two portions joined on opposite ends of said elongated aperture forming two adjacent areas arranged to be set into vibration by the actuation of said poles, said narrow slot operating to substantially prevent interference between the vibrations set up in the respective areas.

3. A telephone receiver diaphragm having an elongated aperture at its center portion consisting of a single slot of varying direction integral with said diaphragm.

4. A telephone receiver diaphragm having an elongated aperture at its center portion consisting of a single slot having a constant width intermediate the ends of said slot and a substantially increased width at opposite ends thereof, said elongated aperture being formed integral and co-planar with said diaphragm.

5. A telephone receiver diaphragm having a single *f* hole positioned midway between the receiver poles.

6. In a double pole telephone receiver, a diaphragm having a single *f* hole at its center portion.

In testimony whereof I affix my signature.

HERMANN FISCHER.
